UNITED STATES PATENT OFFICE.

ERNST CHRISTENSON, OF STOCKTON, KANSAS.

RAILWAY-GATE-OPERATING MECHANISM.

1,411,408.

Specification of Letters Patent.

Patented Apr. 4, 1922.

Application filed March 17, 1921. Serial No. 453,133.

To all whom it may concern:

Be it known that I, ERNST CHRISTENSON, a citizen of the United States, residing at Stockton, in the county of Rooks and State 5 of Kansas, have invented certain new and useful Improvements in Railway-Gate-Operating Mechanism; and I do declare the following to be a full, clear, and exact description of the invention, such as will enable others skilled in the art to which it appertains to make and use the same, reference being had to the accompanying drawings, and to the letters and figures of reference marked thereon, which form a part of 10 this specification.

This invention relates to railway gate operating mechanism and the primary object thereof is to provide means whereby a railway gate or barrier will be moved to obstructing position in response to train-actuated mechanism upon the approach of a train and will be moved out of obstructing position when the train is passing or has 20 passed the crossing guarded by the gate or barrier.

The invention also contemplates a novel form of barrier which will normally obstruct the passage of traffic over the crossing, when the barrier is in obstruction position, 30 but which will yield under pressure so that danger of damage to a car or person who accidentally runs into the barrier will be eliminated.

Means is also provided for operating a signal when the barrier is moving into obstruction position, the signal being preferably an audible one.

The preferred form of my invention is illustrated in the accompanying drawings, 40 in which—

Fig. 1 is a perspective view of a railway crossing to which my invention is applied, the barrier being shown in obstruction position.

Fig. 2 is a detail perspective view of the train-operated trips for controlling the actuation of the operating mechanism.

Fig. 3 is a perspective view of the barrier and its operating mechanism, part of the housing or casing therefor being broken away to illustrate the interior thereof.

Fig. 4 is a perspective view of the barrier.

Fig. 5 is a diagrammatic view of the barrier showing a segmental dog for holding it in its raised position.

Fig. 6 is a similar view showing the dog moving off the segmental rack as the barrier reaches its vertical position, and

Fig. 7 is a like view showing the barrier 60 in its obstruction position, the dog dropped away from the rack.

Referring now to the drawings by numerals of reference:

1 designates a portion of a railroad track 65 and 2 a crossing to be guarded by the barrier or gate constituting one of the elements of my invention.

A suitable distance away from the crossing 2 is a trip 3 consisting of an upstanding lever 4 on a rock shaft 5, journaled in the casing 6 and provided with a rigid cam 7 adapted to contact with the arm 8 of a bell crank lever 9 journaled in the casing. The end 9' of the bell crank lever 9 is in the form 75 of a dog to engage in either of the recesses 10 or 10' of a segmental rack 11, rigid on the shaft 12 in the casing 6.

The rock shaft 12 supports an upstanding slotted lever 13, which is in pivotal engagement with a lever 14 on a shaft 15, journaled in the bracket 16 which is mounted in the housing 17. The shaft 15 carries a shoe or cam 15' adapted to ride against the head 18, which is connected to the vertically movable rack bar 19 through the link 20, rigid with the head 18, the link being in slotted engagement with the bracket 16, as clearly indicated in Fig. 3.

The rack bar 19 is provided at its lower 90 end with an elongated slot 21, through which the shaft 22 projects. The shaft carries a double cam 23 adapted to bear against the step or projection 24, rigid on the lower portion of the rack 19 so that when the shaft 22 is rotated in either direction by actuating mechanism to be later described, the rack bar will be depressed or moved downwardly. This will occur when the trip arms 25 and 25' and arm 4 are adj- 95 cent to the rail to be actuated by the car wheels as the train passes over the track.

The upper end of the vertical rack 19 is connected to the stem 26 of a piston 27 of a dash pot 28 and the piston is normally urged 105 into compression stroke within the dash pot by a spring 29, one end of which is connected to the casing 17 and the other to the rack 19.

The rack is also guided in its upper end 110 in a slotted guide bracket 19', to which one end of a coil spring 30 is attached, the other

end of the spring being connected to an offset 31, integral with the rack bar 19. The normal tendency of the spring 30 is to raise the rack bar 19 and the spring 29 tends to maintain the teeth 32 of the rack bar 19 in engagement with a pinion 33, carrying a spring-pressed pawl 34 to engage a ratchet 35 on a shaft 36, horizontally disposed within the casing 17 and provided with a friction clutch 37 at one end to drive a spur gear 38 in mesh with a gear 39 on a shaft 40, to which the barrier is rigidly secured.

The shaft 40 carries a beveled ratchet gear 41, the beveled teeth of which mesh with a beveled gear 42 on a shaft 43. The shaft 43 carries a fly wheel or weighted rim wheel 44 at one end and at the other a plurality of tappets 45, which may strike against a bell or gong 46 when the shaft 43 is rotated to make an audible signal.

The shaft 40 is also rigidly connected to the barrier arm 47, which is provided with an offset end 48, carrying a supplemental arm 49, pivoted thereto at 50 by an inclined pivot member so that normally the member 49 will be folded back on 47, as shown in Fig. 3, but when the member 47 is in a horizontal position, the inclined pivot 50 will permit the extension arm 49 to gravitate or swing outwardly into extended position, as shown in dotted lines in Fig. 4.

The arm 47 rigid on the shaft 40 also carries a pawl 51, which is adapted to intermittently engage the segmental rack 52, fastened on the side of the casing 17. Adjacent to the shaft 36 is a gear 53 on a shaft 54. The gear 53 meshes with the gear 38 and with the teeth 55 on a counterbalance weight 56, carried by a bar 57, one end of which is movable in a guide 58 and the other provided with a slot 59, through which a headed bolt 60 projects. The counterbalance weight, through the medium of the gears 53, 38 and 39, will tend to counterbalance the barrier consisting of the members 47 and 49, the weight of the weight 56 being slightly less than that of the barrier.

The trip arms 25 and 25' are connected to rock shafts 61 and 62, being normally held in their vertical positions by the springs 63 and 64, which bear against them, the rock shafts 61 and 62 having depending crank arms 65 and 66, connected to the pivot 67 for the levers 13 and 14 by links 68 and 69, the links being normally in conduits 70 and 71 to protect them from rain, sleet and snow and since they communicate directly with the casing 6, none of the operating parts except the trip levers 25 and 25' will be exposed to the elements.

It will be observed that the lever 25 will be operated by an east bound train and the trip 25' will be operated by a west bound train.

When either the trip lever 25 or 25' is

tilted by contact with a wheel, the rock shaft to which it is attached will be rocked and, through the link connection 68 or 69, as the case may be, the lever arm 14 will be swung so as to impart movement to the shaft 15, causing the cam or shoe 15' to ride on the head or shoe 18 and through the link 20, push the toothed portion of the bar 19 out of contact with the gear 33, allowing the gearing consisting of the gear 33, gears 38 75 and 53, counterbalance 56, gear 39 and gears 41 and 42 to run freely and since there will be nothing to hold up the arm 47, the barrier must drop to a horizontal position, such as shown in Fig. 4 and the extended arm 80 will swing outwardly, as shown in dotted lines in Fig. 4.

The gravitation of the arm 47 to a horizontal position will impart an impetus to the shaft 43 through the gears 41 and 42, 85 the inertia of the fly wheel 44 imparting a continuous rotation to the shaft 43 after the arm 47 has moved to horizontal position since the gears 41 and 42 may run independent of any movement of the shaft 90 40. As the shaft continues to spin in its bearings, the tappets 49, which may be yieldingly connected to the shaft 43, will strike against the gong or bell 46 for a considerable time after the barrier is in its 95 obstructing position.

If, by any chance, the barrier happens to be struck, that is, if the arm 49 should happen to be struck by a motor vehicle or contacted with by a horse or other animal, the 100 arm will give sufficiently to prevent wrecking the barrier.

When the arm 14 is swung in either direction, it is obvious that the shaft 12 will also be rocked through the medium of the 105 arm 13 so that the toothed portion 9' of the elbow lever 9 will drop into one of the notches 10 or 10', thereby holding the arm 14 in position so that the cam 15 will remain in its locked position against the head 18 and 110 through the link 20, hold the lever 19 out of engagement with the teeth of the ratchet wheel 35 so that the gate can move to its horizontal position, the rack bar 19 being maintained out of engagement with its ratchet 115 wheel during this time. Then when the first wheel in the train strikes the arm 4, the shaft 5 will be rocked, causing the cam 7 to strike against the arm 8 of the elbow lever 9 and withdraw the detent or dog 9' from 120 engagement with the notch in the segment 11, permitting the spring 29 to pull the bracket back into toothed engagement with its ratchet wheel.

At the same time the rock shaft 5 will 125 cause the double cam 23 to bear upon the foot or flange 24 to impart a downward movement to the rack bar 19 against the spring 30. The downward movement of the rack bar 19 will rotate the gear 33 and, 130

through the gear 33, rotate the shaft 36, imparting motion to the gear 38, the gear 39 and shaft 40 so that the barrier will be raised slightly with a step-by-step movement as 5 the wheels of the train continue to strike against the arm 4.

The first time the wheels strike against the arm 4, the gear will rotate the shaft 40 sufficiently to allow the dog 51 to engage in 10 the first or second tooth of the rack 52, rigid on the casing 17. The next time the arm 4 is struck, the barrier will be swung to a slightly greater arc, the dog 51 engaging the proper tooth to hold it in that position, and 15 this will continue until the barrier is raised to a vertical position, when it will drop off the dog as shown in Fig. 3.

If the train is a long one and the arm 4 is actuated a greater number of times than will 20 be necessary to raise the barrier to a vertical position, the shaft 36 will continue to rotate but on account of the slip clutch 37, the gear 38 will not be rotated. The continued movements of the arm 4, cam 22 and rack 19 will 25 continue to rotate shaft 36 without rotating the gear 38, the resistance of the barrier 47 being sufficient to allow the shaft 36 to rotate without rotating the gear 38.

When the train strikes the arms 25 or 25', 30 as the case may be, and the rack teeth are pushed away from the gear 33, there should be a time element involved; that is, the teeth on the rack 19 should not engage the gear 33 until the barrier has dropped to its horizontal position. This is provided for by the dash pot 28, which will allow the piston 27 to move outwardly to draw air in through the pet cock 72, which may be regulated, but as soon as the wheel passes over the arms 25 40 or 25' and the rack has moved away from its gear, the barrier will start to move to a horizontal position and during this time the rack will be moved back into engagement with the gear 33, the time required being determined by the pet cock 72.

It will also be apparent that the detent 9' 45 constitutes a positive lock to hold the rack 19 out of engagement with its ratchet wheel during the time that the gate is moving to a horizontal position, the timing device consisting of the dash pot or check being capable of operating only after the train has actuated the arm 4 to release the detent 9' from engagement with the notch 10 or 10', 55 as the case may be.

It will, therefore, be seen that the device is automatic in its operation and that it may be actuated from either side of the crossing.

What I claim and desire to secure by Letters-Patent is:

1. A railway gate operating mechanism comprising a shaft, a ratchet wheel on said shaft, a reciprocating rack for operating the ratchet wheel, a spring normally urging the 65 rack in one direction, a spring connected to

the rack to normally hold it in engagement with the ratchet wheel, a train-actuated cam for reciprocating the rack against the action of the first named spring, train-actuated means for releasing the rack out of engagement with the ratchet wheel to allow its shaft to turn independently of the rack, and a barrier controlled by the shaft, movable into obstructing position when the ratchet wheel is released from the rack. 70

2. A railway gate operating mechanism comprising a shaft, a ratchet wheel on said shaft, a reciprocating rack for operating the ratchet wheel, a spring normally urging the rack in one direction, a spring connected to the rack to normally hold it in engagement with the ratchet wheel, a train-actuated cam for reciprocating the rack against the action of the first named spring, train-actuated means for releasing the rack out of engagement with the ratchet wheel to allow its shaft to turn independently of the rack, a barrier controlled by the shaft, movable into obstructing position when the ratchet wheel is released from the rack, 75 80

weight for the barrier having rack teeth, a gear meshing with the rack teeth, and a gear on the first named shaft meshing with the gear which is in mesh with the rack teeth. 85

3. A railway gate mechanism comprising a casing, a horizontal shaft in said casing, a ratchet wheel for driving said shaft, a reciprocating rack having teeth for engagement with the teeth of the ratchet wheel, a projection on the rack, a train-actuated cam 100 for longitudinally moving the rack in one direction to actuate the ratchet wheel so as to turn its shaft, a tension spring for moving the rack in an opposite direction, a train-actuated means for moving the rack out of engagement with the ratchet, a dash pot for timing the return movement of the rack to mesh with the ratchet wheel, a barrier shaft driven by the first named shaft, and a barrier on the second mentioned shaft. 110

4. A railway gate operating mechanism comprising a casing, a shaft in said casing, a ratchet wheel on said shaft adapted to rotate the shaft in one direction but to rotate idly about the axis of the shaft in an opposite direction, a ratchet-actuating rack bar normally in mesh with the ratchet, train-actuated means for moving the rack bar in one direction to rotate the ratchet to turn its shaft, a spring for retracting the rack bar 115 to rotate the ratchet idly about its shaft, train-actuated means for temporarily moving the rack bar out of mesh with the ratchet, and a barrier actuated by the shaft. 120

5. A railway gate operating mechanism comprising a casing, a shaft in said casing, a ratchet wheel on said shaft adapted to rotate the shaft in one direction but to rotate idly about the axis of the shaft in an opposite direction, a ratchet-actuating rack bar 125 130

- normally in mesh with the ratchet, train-
actuated means for moving the rack bar in
one direction to rotate the ratchet to turn its
shaft, a spring for retracting the rack bar
5 to rotate the ratchet idly about its shaft,
train-actuated means for temporarily moving
the rack bar out of mesh with the ratchet, a
spring normally urging the rack bar into
engagement with the ratchet wheel, a check
10 to yieldingly oppose the movement of the
rack bar into engagement with the ratchet
wheel, and a barrier actuated by the shaft.
16. A railway gate operating mechanism
comprising a casing, a shaft in said casing,
15 a ratchet wheel mounted on the shaft to ac-
tuate the shaft when the wheel turns in one
direction and to turn idly in an opposite di-

rection about the axis of the shaft, a recip-
rocatory rack bar normally in mesh with the
ratchet wheel, a projection on the rack bar, 20
a train-actuated rock shaft, a cam on the
rock shaft to ride on the projection on the
rack to impart longitudinal movement there-
to in one direction, a spring for retracting
the rock shaft, an arm pivoted to the rack, 25
a train-actuated rock shaft having a part to
ride on the end of the arm to move the rack
out of engagement with the ratchet wheel,
means for returning the rack into mesh with
the ratchet wheel, means for yieldingly re- 30
sisting the return movement, and a barrier
controlled by the first named shaft.

In testimony whereof I affix my signature.
ERNST CHRISTENSEN.
